UNITED STATES PATENT OFFICE.

SIDNEY O. BIGNEY, OF ATTLEBORO, MASSACHUSETTS.

DESIGN FOR A WATCH-CHAIN CHARM.

42,910.

Specification for Design.

Patented Aug. 20, 1912.

Application filed May 15, 1912. Serial No. 697,556. Term of patent 14 years.

To all whom it may concern:

Be it known that I, SIDNEY O. BIGNEY, a citizen of the United States, residing at Attleboro, county of Bristol, State of Massachusetts, have invented a new, original, and ornamental Design for a Watch-Chain Charm, of which the following is a specification, reference being had to the accompanying drawing, forming part thereof.

Figure 1 is a front elevation showing my improved design of watch chain charm, and Fig. 2 is an edge elevation of the same.

I claim:

The ornamental design for a watch chain charm as shown.

SIDNEY O. BIGNEY.
